[57] CLAIM

The ornamental design for a bladder for a tape dispenser, as shown and described.

DESCRIPTION

FIG. 1 is a perspective view of a tape dispenser showing my new design;

FIG. 2 is a front elevational view of the tape dispenser shown in FIG. 1;

FIG. 3 is a rear elevational view of the tape dispenser shown in FIG. 1;

FIG. 4 is a left side elevational view of the tape dispenser shown in FIG. 1, the opposite side being the mirror image of that shown;

FIG. 5 is a bottom plan view of the tape dispenser shown in FIG. 1;

FIG. 6 is a top plan view of the tape dispenser shown in FIG. 1; and,

FIG. 7 is a cross-sectional view through the tape dispenser taken along line 7—7 in FIG. 3.
